UNITED STATES PATENT OFFICE.

EMIL WILLIAM ANDERSEN, OF AARHUS, DENMARK.

KILN FOR DRYING VEGETABLE SUBSTANCES.

1,218,156.

Specification of Letters Patent.

Patented Mar. 6, 1917.

Application filed August 4, 1915. Serial No. 43,563.

To all whom it may concern:

Be it known that I, EMIL WILLIAM ANDERSEN, a subject of the King of Denmark, residing at Aarhus, Denmark, have invented 5 a new and useful Kiln for Drying Vegetable Substances; and I do hereby declare the following to be a full, clear, and exact description of the same.

The invention relates to a kiln meant for 10 drying of vegetable substances such as oil seed and especially copra. The kiln in question is distinguished by being arranged for effecting the drying of the copra or the material in question by a combination of the 15 warmth of the sun and artificial heat, whereby in practice is obtained a considerably quicker drying than in previously known kilns for this purpose, which has a favorable influence on the look and quality of the dried 20 product. The combined use of warmth of the sun and artificial heat as it is practised by the present invention further insures an essential saving of fuel, and the shells of the dried copra in a plant like the present 25 one yield fully sufficient fuel for the kiln. The invention essentially consists in a kiln heated from below in a known manner, adapted for accommodation of the copra or the material in question being covered by a 30 glass roof whereby the heat from the sun beams is intensely concentrated in the drying room, which is further in suitable places provided with suitable openings which can be closed more or less by means of shutters 35 or the like, by means of which a suitable ventilation of the drying room is obtained for removal of moisture or humid air formed.

Other features of the invention will appear from the following specification with 40 thereto belonging drawings, in which Figure 1 shows a suitable type of kiln according to the invention in end-view partly in section on the line 1—1 in Fig. 2, and Fig. 2 a side view of the kiln.

The lowermost part of the kiln is constructed of brick work and contains two fire places *a*, meant for being heated with a suitable fuel, preferably the shells removed from the dried copra, and above the fire 45 places is arranged a horizontal hearth or salver *b* in which is spread a layer of sand *c* some inches deep which is able to store a considerable amount of heat, and on top of

the sand is arranged a layer of flagstones *k* on which the copra *d* or the material in question to be dried is placed. The combustion products are led away through the two funnels *e* each of which is provided with a suitable damper *f*. Over the hearth and the drying room above the same is arranged 55 an oblique glass roof *g*, and at the uppermost and lowermost edges of the same are suspended valves *h* which open and close corresponding openings through which a natural draft of air can pass as indicated by 60 the arrows.

When the kiln is used for instance for drying of copra the same is spread on the flagstone hearth *k*, and the kiln is heated two times a day and night, for instance at 6 o'clock in the morning and at 6 o'clock in the evening, with the shells from a previous drying. When the shells are burned so much that only red hot embers are left, the fire doors are shut and the draft is subdued 70 by means of the dampers *f*, so as to obtain a quiet and slow yielding of heat to the layer of sand and the flagstones and to the layer of copra resting on the latter. The sun beams shining during the day through the 75 glass roof *g* further the drying to a high degree, and through a suitable adjustment of the dampers *h* a suitable renewal of air in the drying room is effected.

The form described is only to be considered as an example and the invention is not restricted to this form but relates to any drying kiln for vegetable materials in which is used a hearth heated from below and covered by a glass roof.

Having now described my said invention and in what manner the same is to be performed, what I claim and desire to secure by Letters Patent of U. S. A. is:

A kiln for drying vegetable material, comprising a fireplace wherein dried copra shells may be burned, a horizontal hearth arranged over the fireplace for supporting the material to be dried while protecting it from the products of combustion, the hearth being 95 of the heat-storage type and adapted during its heat-radiation to radiate heat uniformly over its entire upper surface, a glazed roof spaced above the hearth to establish a drying chamber having substantially a triangular cross-section, and a plurality of ad-

justable ventilators, one located adjacent the uppermost and another adjacent the lowermost edge of the roof and both vertically suspended when closed, whereby a dehumidi-
5 fying air current may traverse the drying chamber, and while continuously ascending adjacent to and parallel with the under surface of the glazed roof may thereby equalize

the amount of solar heat delivered to the various portions of the material being dried. 10

In testimony whereof I affix my signature in presence of two witnesses.

EMIL WILLIAM ANDERSEN.
